[57] CLAIM

The ornamental design for a keyboard stand for a telephone handset transceiver, as shown and described.

DESCRIPTION

FIG. 1 is a left side, top and front perspective view of a keyboard stand for a telephone handset transceiver showing my new design;

FIG. 2 is a left right side elevational view thereof;

FIG. 3 is a rear elevational view thereof;

FIG. 4 is a bottom plan view thereof; and

FIG. 5 is a left side, top and front perspective view of a second embodiment thereof, the only difference from the first embodiment being in the arrangement of the keyboard pattern.

FIG. 2

FIG. 3

FIG. 4

FIG. 5
